TUMBLER PAD FOR DRYING MACHINES

Sam M. Hyman, Manitowoc, Wis.

Application November 1, 1951, Serial No. 254,293

4 Claims. (Cl. 259—1)

1

This invention relates to tumbler pads for use on the baffles of the rotary drums in drying machines in the cleaning industry to prevent button breakage or other damage to garments tumbled in the dryer.

While tumbler type dryers, equipped with internal ribs or baffles, provide a generally accepted type of machine for accomplishing the desired end, they have presented the universal problem of breaking or tearing buttons from garments while they are being tumbled. Numerous attempts have been made to provide suitable cushioning pads for the baffles of this type of machine to overcome the above mentioned problem.

Due to the relatively high temperature of operation of these dryers, frequently in the neighborhood of 350° Fahrenheit, and the presence of considerable moisture in the machine, the majority of the previously designed cushioning pads have failed to give satisfactory service either from the standpoint of results accomplished or the duration of the life of the pads.

The present invention constitutes an improvement on my original idea relating to plastic covered tumbler pads as disclosed and claimed in my U. S. Patent No. 2,480,929.

The primary object of the present invention is to provide a new and improved tumbler pad adapted to overcome the major difficulties experienced with most of the devices previously used and the minor difficulties encountered in the use of other of the devices.

An another object of the present invention resides in the provision of a new and improved tumbler pad having a relatively smooth slick surface, formed of plastic, nylon or similar material covering a cushioning portion to thereby afford a device having vastly improved operating characteristics in the form of greatly increased wear resisting properties coupled with materially lessened damage to the processed garments.

Another object of the present invention resides in the provision of a new and improved tumbler pad including a relatively smooth garment contacting surface formed of plastic or like material backed by a cushion of resilient material such as felt, foam rubber, fiber glass or other suitable yieldable material capable of withstanding the effects of high temperatures and the presence of considerable moisture.

Another object of the present invention resides in the provision of a new and improved tumbler pad constructed in a manner to afford the optimum protection against button breakage

2

or other damage to the garments by protecting the same against contact with the raw edges of the plastic material.

Other objects and advantages will become apparent from the following description of the illustrative embodiments of the present invention shown in the accompanying drawing.

In the drawing:

Figure 1 is a top plan view of a tumbler pad constructed in accordance with the teachings of the present invention and having parts broken away to more clearly illustrate its structure;

Fig. 2 is an enlarged vertical transverse sectional view, taken on the line 2—2 of Fig. 1, showing the construction of the pad;

Fig. 3 is an enlarged fragmentary vertical longitudinal sectional view, taken on the line 3—3 of Fig. 1, showing the structure of an end hem at the cushion portion of the pad;

Fig. 4 is a view similar to Fig. 3, taken on the line 4—4 of Fig. 1, showing the end hem adjacent its longitudinal marginal edge;

Fig. 5 is a vertical transverse sectional view taken through one of the baffles of the dryer and showing the tumbler pad in functioning position on the same;

Fig. 6 is a fragmentary top plan view of a modified form of the tumbler pad shown in Fig. 1;

Fig. 7 is an enlarged fragmentary vertical longitudinal sectional view, taken on the line 7—7 of Fig. 6, showing the means for attaching the plastic covering to the cushioning portion of the tumbler pad in a manner to prevent contact of the raw edge of the covering with the garments in the dryer; and

Fig. 8 is a view similar to Fig. 7 showing a further modified form of the invention wherein the raw marginal edge of the plastic covering is protected against contact with the garments in the dryer by the application of a binding tape around the marginal edge of the tumbler pad.

Before entering into a detailed description of the various forms of the invention shown in the accompanying drawing, it is believed that a brief description of the application to which the tumbler pad is put will serve to emphasize its several advantages. At the outset, the tumbler type dryer includes a casing housing a perforated rotary drum having a plurality of longitudinally disposed inwardly projecting baffles which serve to contact the clothes and tumble the same as the drum is rotated. Obviously, the impact of the baffles with the garments, as the garments are thrown in the drum, would

cause considerable button breakage and other damage to the garments in the absence of a shock absorbing covering for the baffles. In addition to shock absorbing properties, the covering for the baffles should provide wear resisting qualities which will insure a reasonably long useful life span. The inherent conditions in which the tumbler pads are called upon to function, at relatively high temperature and high humidity, tend to cause very rapid wear on the fabric cover by reason of the rubbing contact between the baffle covers and the tumbled garments. Under the most favorable conditions, the life span of fabric covered tumbler pads is so short that their use becomes expensive; not only from the standpoint of replacement cost but also in the loss of machine operating time and the labor of their replacement.

While the use of plastic covered pads, of the type described and claimed in my earlier mentioned patent, have provided a device with vastly improved wearing properties due to the nature of the plastic material; I have found that in some instances damage to the tumbled garments has resulted from exposed raw edges of this plastic material which tends to have its exposed edges crack and become brittle under the high temperature of the dryer.

The present invention is directed to an improvement in the structure of the tumbler pad to overcome this slight defect by providing a device in which none of the raw edges of the plastic covering material are exposed to contact the tumbled garments.

The tumbler pad chosen for illustrative purposes in Figs. 1 to 5, inclusive, in the accompanying drawing and constructed in accordance with the teachings of the present invention comprises generally a pad 10 having a cushion member 11 formed of resilient material such as felt, foam rubber, fiber glass or similar material and a covering 12 formed of plastic or similar material. In this form of the invention, the cushion member 11 extends substantially the full length of the pad 10 and is secured in proper position on a canvas base 13 by means of parallel stitchings 14 which extend the length of the cushioning member. The upper portion of the pad 10 includes the plastic cover 12 to which a pair of canvas strips 15 are attached along the longitudinal marginal edges of the cover 12 by means of three thread overedge stitching 16. The overall width of the upper portion of the pad 10 is greater than the width of the base 13, before the two parts are joined together, so that when the longitudinal marginal edges of the strips 15 and base 13 are aligned the plastic cover 12 fits loosely over the cushion member 11. With the upper and base portions of the pad properly arranged, the two are joined together by means of parallel stitchings 17 extending lengthwise of the pad and disposed adjacent the edge of the cushion member 11 and the stitchings 16. The longitudinal marginal edges of the base 13 and the strips 15 are joined by three thread overedge stitching 18. End hems 19 are formed on the pad 10 by turning the ends of the base 13 over the upper portion of the pad and applying two parallel lines of stitching 20. The pads are completed by the application of a plurality of eyelet grommets 21 in parallel arrangement adjacent the longitudinal marginal edges of the pad 10.

In actual use, one of these pads 10 is applied to each of the baffles of the drying machine. In

Fig. 5 I have illustrated a pad 10 applied to a baffle 22 which is U-shaped with its closed portion projecting toward the center of the drum. Suitable holes 23 are formed in the sides of the baffle 22 to receive anchoring means for retaining the pad in position on the baffles. Each lower marginal edge of the baffle 22 is provided with a series of tangs 24 adapted to extend through holes or perforations 25 formed in the cylindrical wall of a drum 26. The baffles are secured in place in the drum by clinching the tangs 24 against the outer surface of the drum 26. The pad 10 is releasably retained in proper position upon the baffle by means of spring clips 27 which are inserted through the aligned grommets 21 in the pads and the holes 23 in the baffle 22.

In the modified form of tumbler pad shown in Figs. 6 and 7 the pad 10' comprises a cushion portion 11' and a covering 12' formed of plastic material. In this form, it will be noted that the cushion member 11' is coextensive with the size of the pad 10' and that the cover 12' is larger in both directions than the other member. To form the pad in the desired manner, the normally projecting marginal edge of the cover 12' is turned under the marginal edge of the cushion member 11' and the parts are joined by stitching 28 which extends completely around the pad 10'. In this manner it will be seen that the pad 10' is so formed that the marginal edge of the cover 12' cannot come in contact with the garments contained in the dryer. The pad 10' is completed by the application of a plurality of grommets 21' which are positioned and arranged to function in the manner previously described.

In the form of tumbler pad shown in Fig. 8, the pad 10'' is similar to that shown in Figs. 6 and 7, and comprises a cushion member 11'' and a cover member 12''. In the present instance, the two parts are identical in size and shape and a binding tape 29 is applied to the marginal edge of the pad 10'' and the several parts are joined together by stitching 30 which extends completely around the pad. It will also be noted that this form of pad provides a construction which prevents the marginal edge of the cover from coming into contact with the garments contained in the dryer.

From the foregoing description of the several forms of the invention it will readily be seen that a new and improved tumbler pad has been provided which will not only withstand strain and abrasive wear by reason of the wear resistant property of the cover but one which affords greater protection against button breakage or other damage to the garments under treatment by reason of the fact that its construction insures against contact of the garments with the raw edge of the covering material of the pad which frequently tends to become brittle and crack under the influence of the high temperature in the dryer.

The term "plastic" as used in the foregoing description and the appended claims is to be construed in its broader sense and is not used with the intent of defining a single specific material. Obviously, nylon or any one of a number of other materials, having similar wear resisting properties coupled with a relatively smooth slick surface, would serve with equal facility in providing a device constructed in accordance with the teachings of the present invention.

The fundamental concept of the present invention resides in the provision of a new and improved tumbler pad having a cushion member

provided with a covering having a relatively smooth slick wear resistant property to prolong the useful life of the pad. A particular advantage of the present pad is found in the provision of a construction wherein the raw marginal edge of the cover is protected in a manner to prevent its coming into contact with the garments under treatment so as to materially reduce any possibility of damage to the garments.

From the foregoing description of the several forms of the invention, it will readily be seen that a new and improved tumbler pad has been provided which will not only withstand strain and abrasive wear by reason of the presence of a covering formed of relatively smooth slick wear resistant material but one which affords greater protection against button breakage or other damage to the garments under treatment by reason of its construction which insures against contact of the garments with the raw edge of the covering material of the pad.

While the invention has been described in considerable detail in the foregoing specification, it is to be understood that various changes may be made in its embodiments without departing from or sacrificing any of the advantages herein-after claimed.

I claim:

1. A tumbler pad for application to the baffles of a drying machine or the like, said pad comprising a base portion substantially co-extensive with surface of the baffle to be covered and including a cushion member, an upper portion including a cover of plastic material having an area sufficient to cover said cushion member, said plastic material serving to increase the wear resistant properties of the pad and afford only a relatively smooth surface for contact with the garments under treatment, fabric means attached to the entire raw marginal edge of said plastic material to form a protective covering for the same to preclude contact between the raw marginal edge of said plastic material and garments under treatment in said machine, and means for securing base and upper portions of said pad to forming a unitary structure.

2. A tumbler pad for application to the baffles of a drying machine or the like, said pad comprising a base portion substantially co-extensive with the surface area of the baffle to be covered and including a cushion member, an upper portion including a cover of plastic material having an area sufficient to cover said cushion member, said plastic material serving to increase the wear

resistant properties of the pad and afford only a relatively smooth surface for contact with the garments under treatment, fabric means secured by stitching disposed adjacent the raw marginal edge of said plastic material to preclude contact between the raw marginal edge of said plastic material and garments under treatment.

3. A tumbler pad for application to the baffles of a drying machine or the like, said pad comprising a base portion substantially co-extensive with the surface area of the baffle to be covered, a cushion member disposed longitudinally of said base portion and secured thereto, said cushion member being narrower than said base portion, an upper portion including a pair of side marginal strips of fabric material and a central portion of plastic material, said strips and central portions being joined along their adjacent marginal edges, said central portion of plastic material an area sufficient to cover said cushion member, said plastic material serving to increase the wear resistant properties of the pad and providing a relatively smooth surface for contact with the garments under treatment, a fabric binding means secured to the end raw edges of said central portion of plastic material to form a protective covering therefore to completely enclose the raw marginal edge of said central portion of plastic material to preclude contact between the raw marginal edge of said plastic material and garments under treatment.

4. A tumbler pad for application to the baffles of a drying machine or the like, said pad comprising a base portion including a yieldable cushion member, an upper portion including a cushion covering formed of plastic material to increase the wear resistant properties of the pad and provide a relatively smooth slick surface for contact with garments under treatment, fabric means attached to the entire raw marginal edge of said plastic material to form a protective covering for the same to preclude contact between the raw marginal edge of said plastic material and garments under treatment in said machine, and means for securing said base and upper portions of said pad into a unitary structure.
